UNITED STATES PATENT OFFICE

131,793

DESIGN FOR A COMBINED CANDLE AND HOLDER OR THE LIKE

Cameron Turner, Beverly, Mass.

Application December 16, 1940, Serial No. 97,353

Term of patent 7 years

To all whom it may concern:

Be it known that I, Cameron Turner, a citizen of the United States and a resident of Beverly, in the county of Essex and Commonwealth of Massachusetts, have invented a new, original, and ornamental Design for a Combined Candle and Holder or the like, of which the following is a specification, reference being had to the accompanying drawing, forming a part thereof, wherein

Fig. 1 is a view in side elevation of a combined candle and holder showing my new design,

Fig. 2 is a top plan view of the base of the device shown in Fig. 1.

The design is characterized by vertical parallel side candle members connected by intersecting cross-over candle members, the whole being supported by a rectangular base as shown.

I claim:

The ornamental design for a combined candle and holder or the like, substantially as shown and described.

CAMERON TURNER.
